US00D574551S

(12) **United States Design Patent**
Park

(10) **Patent No.:** **US D574,551 S**
(45) **Date of Patent:** **** Aug. 5, 2008**

(54) **LENS FOR LIGHT EMITTING DIODE**

(75) Inventor: **Kwang Il Park**, Seoul (KR)

(73) Assignee: **Seoul Semiconductor Co., Ltd.**, Seoul (KR)

(**) Term: **14 Years**

(21) Appl. No.: **29/235,148**

(22) Filed: **Jul. 27, 2005**

(30) **Foreign Application Priority Data**

Feb. 2, 2005 (KR) 30-2005-0003555

(51) **LOC (8) Cl.** **26-99**

(52) **U.S. Cl.** **D26/120**

(58) **Field of Classification Search** **D26/139, D26/142, 152, 77, 76, 37, 123, 128, 120, D26/118, 113, 138, 3, 28, 72, 124, 121, 122, D26/75, 79, 90, 105; D13/180; 362/614, 362/611, 612, 632, 555, 516, 147, 148, 216, 362/217, 260, 291, 296, 297, 341, 346, 404, 362/407, 431, 800**

See application file for complete search history.

(57) **CLAIM**

The ornamental design for lens for light emitting diode, as shown and described.

DESCRIPTION

FIG. 1 is a perspective view of a lens for light emitting diode showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
